UNITED STATES PATENT OFFICE.

FREDERICK A. BALLOU, JR., OF PROVIDENCE, RHODE ISLAND, ASSIGNOR TO B. A. BALLOU & CO. INC., OF PROVIDENCE, RHODE ISLAND, A CORPORATION OF RHODE ISLAND.

SAFETY-CATCH.

1,262,734.

Specification of Letters Patent. Patented Apr. 16, 1918.

Application filed October 12, 1916. Serial No. 125,162.

To all whom it may concern:

Be it known that I, FREDERICK A. BALLOU, Jr., a citizen of the United States, and resident of the city of Providence, in the 5 county of Providence and State of Rhode Island, have invented certain new and useful Improvements in Safety-Catches, of which the following is a specification.

This invention relates to locks for safety 10 catches for pins, and has for its object to provide a keeper having a pair of laterally yieldable side walls or ears and a guard member rotatably mounted between said ears and adapted to be locked in either open 15 or closed position, both said keeper and guard being provided with a slot opening in its margin, the guard being movable to open or close the slot in the keeper.

A further object of the invention is the 20 provision of an inwardly projecting protuberance on one or both of the side walls of the keeper for engaging the slot in the guard to yieldably retain the latter in closed position.

25 A still further object of the invention is to provide means in the guard and keeper whereby the guard may be locked in either open or closed position by the action of said protuberance.

30 The invention further consists in the provision of means whereby a double lock is provided so that if the guard should be moved past the first lock it will engage the second lock before finally being moved to 35 open the catch.

With these and other objects in view, the invention consists of certain novel features of construction, as will be more fully described, and particularly pointed out in the 40 appended claim.

In the accompanying drawings:

Figure 1— is a side elevation of a pin showing the point of the pin stem retained in my improved safety catch.

45 Fig. 2— is a perspective view showing the protuberance on the inner wall of one of the side ears of the keeper, the second wall having been removed.

50 Fig. 3— is a perspective view of the guard member showing the slot, the cut away portion and the recessed portion all of which serve to coöperate with said protuberance for locking the guard either in open or closed position.

Fig. 4— is an edge view showing both 55 sides of the keeper in position to be bent up over the trunnions of the guard, to connect the whole together.

Fig. 5— is a side elevation of the catch member showing the guard in position to 60 close the mouth of the slot in the keeper.

Fig. 6— is a diagrammatic view showing the development of the guard mounted in the keeper, the latter being in closed position with the protuberance engaging the 65 slot therein.

Fig. 7— is the same as Fig. 6 with the guard moved forward in position for the protuberance on the keeper to engage the second stop on the guard to further prevent 70 the guard from moving to open position.

Fig. 8— shows the guard as having moved to open position and the protuberance in the wall of the keeper as having entered 75 the recesses in the side of the guard to retain the same yieldably in closed position.

This invention is an improvement on Patent No. 1034136 to Morehouse and shows another means by which the guard member 80 may be held in closed position, and also means for retaining the guard in open position.

Referring to the drawings in the present case, 10 designates the usual pin stem pivotedly mounted at one end in the joint member 11 attached to the body 12. My improved safety catch member 13 may be formed integral or it may be separate and subsequently attached to the pin body and 90 is for the purpose of receiving the locking pivoted end of the pin stem.

This catch may be constructed in any suitable way but for convenience I have formed the keeper portion of two side ears 95 14 and 15 which are preferably bent up from a common base 16, the same being countersunk as at 17 for the reception of the trunnions 18 on the guard member 19. These side ears are each provided with a slot 20 which extends inward from its margin to the center thereof for the reception of the pointed end of the pin stem. The guard member is also provided with a similar slot 22 adapted to register with those in the ears 100 23 of the keeper when the handle portion 105 of this guard is placed in the position illustrated in dotted lines in Fig. 5, and when

this guard member is moved so that this handle is in the position illustrated by full lines in Fig. 5, the slot 22 as in the up position which serves to close the slots in the 5 ears and lock the pin stem in the keeper.

In some instances in devices of this character the friction of the two parts is depended upon to hold the guard in any position in which it may be placed. It is found that 10 this construction is not to be relied upon as the parts wear and the nature of the stock varies considerably and therefore a uniform grip of the walls of the keeper against the guard member cannot be relied upon.

15 To overcome this difficulty I have provided a positive lock which will retain the guard either in closed or open position in the keeper.

To accomplish this I have provided a protuberance 24 on the inner face of each of 20 these ears 14 and 15 in such position that they will both enter the slot 22 in the keeper when it is moved into position to close the slot 20 in the ears.

25 I have also provided recesses 25 in the side faces of the guard member which will engage these protuberances 24 and retain the guard when moved to open position.

In order to render the action of this catch 30 practical and most effective I have reduced the side walls of the guard member at the point 26 between the slot 22 and the recesses 25 whereby this portion of the guard member may receive a free movement past the 35 protuberances 24 and I have also provided a second pair of shoulders 27 on the guard member which are adapted to engage the protuberances just before the slot 22 on the guard registers with slots 20 on the keeper 40 thereby providing a second lock or stop to prevent the guard from moving to open position without being forced even though it should have passed the shoulders of the first lock.

45 In the operation of my improved safety catch when the guard is moved to locked position, the protuberances 24 enter the slot 22 from opposite sides. When it is desired to move the guard to open position pressure

is brought to bear upon the handle 22 to 50 rotate the guard which causes the side walls 14 and 15 of the keeper to yield sufficiently to permit the enlarged portion 28 of the wall 29 of the guard member to pass by, after which the wall comes back to normal 55 and the protuberances enter the cut-away portion 26, the guard now rotates freely until these protuberances bring up against the shoulder 27. Here again the guard is prevented from the free forward movement, requiring pressure to force the side walls open 60 to permit the protuberances to pass over into the recesses 25 at which point the slot 22 registers with the slots 20 in the keeper.

Both the shoulders 27 and 30 are preferably somewhat sloping to act as a wedge upon the protuberances and cause the walls to yield somewhat easily in permitting said protuberances to pass both into and out of the recesses 25, the shoulders 31 being sharp 70 so as to offer considerable resistance to the first movement of the guard from its closed or locked position.

I have shown and described protuberances on both walls of the keeper, but the protuberances on but one wall may be employed if desired.

I have shown and described one illustrative embodiment of my invention but I desire it to be understood that although specific terms are employed they are used in a descriptive and generic sense and not for the purpose of limitation, the scope of the invention being defined only by the appended claim.

85 I claim:

In a safety catch, a keeper having a pair of laterally yieldable side ears, a guard member having trunnions rotatably mounted in said ears, said keeper and guard each being provided with a slot opening on its margin, said guard being movable to open or close the slot in the keeper, and a protuberance on the wall of said ears for engaging said slot in the guard to hold the latter in closed position.

90 In testimony whereof I affix my signature.

FREDERICK A. BALLOU, JR.
